APPARATUS FOR DEFROSTING REFRIGERATING COILS

Isaiah G. Furnas, Chicago, Ill.

Application March 21, 1932, Serial No. 600,166
Renewed July 12, 1934

11 Claims. (CL 62—115)

This invention relates to a coil defrosting mechanism and will be described as employed for the defrosting of cooling coils associated with a refrigerator system.

5 An object of this invention is the provision of mechanism whereby accumulated frost may be readily and quickly removed from refrigerating coils without interfering with the normal operation of the refrigerating system and without the necessity of shutting down the system or any part thereof even for a short time.

Another object is the provision of such a device adapted to break loose the congealed or coagulated oil film from the inner walls of such a refrigerating coil, more economically and efficiently than has been done heretofore.

10 The accumulation of an appreciable amount of frost on the outer surface of a refrigerating coil, or the accumulation of a coagulated film of oil on 20 the inside very materially insulates the coil from the air in the compartment to be refrigerated. As a result, it restricts the flow of heat from the cooling compartment to the interior of the coil thereby cutting down the efficiency of the system, and making the system uneconomical particularly when extremely low temperatures are required as in the quick freezing systems because of the additional refrigerating capacity required 25 to maintain the desired low temperature.

30 Heretofore it has been the practice to bypass the refrigerating condenser, and allow the compressed hot gases to pass through the cooling coils, to heat the coils and defrost them. An obvious disadvantage of such practice is that all 35 the cooling coils are heated at one time, thus throwing the entire system out of operation for a sufficient time to carry out the defrosting operation. Not only this, but the heat from all the cooling coils of the system is sufficient to materially raise the temperature of the compartment 40 to be refrigerated, resulting in the rising of the temperature of the stored goods or necessitating their removal before the defrosting operation is attempted. Such a defrosting operation prevents the maintenance of uniform temperature 45 in the storage compartment which is very detrimental to the quality of goods which are preserved by refrigeration.

50 One of the important objects of my invention is, therefore, the provision of a device which will obviate the disadvantages above pointed out, and which will quickly and efficiently defrost the coils by sections while the refrigerating plant is operating and without interfering with the main-

tenance of a uniform temperature in the storage or refrigerating compartment.

Other objects and advantages of this invention will appear from the following description with reference to the accompanying drawing.

5 On the drawing:

Figure 1 is a perspective view illustrating my invention and showing the refrigerating coils diagrammatically, also illustrating a wiring diagram for electrical connection to the bus bars.

10 Figure 2 is a perspective view of a switch member adapted to connect the bus bars electrically to the refrigerating coils.

Figure 3 is a perspective view of a form of clamp which may be used for connecting one of 15 the bus bars to the refrigerating coils and for similar purposes.

Figure 4 is a diagrammatic view of one form of my invention.

Figure 5 is a diagrammatic view of a modification of my invention.

Figure 6 is a diagrammatic view of another modification of my invention.

Figure 7 is a diagrammatic view of still a further modification of my invention, and

25 Figure 8 is a diagrammatic view of a controlling apparatus which may be employed with my invention.

As shown on the drawing:

In Figures 1 and 4 to 7 inclusive, numeral 5 30 designates a cooling coil for a refrigerating system. Such a coil usually consists of a large number of connected pipes 6 or a continuous pipe which is bent at the end and folded back along itself many times or coiled in various manners 35 to best fit the compartment in which it is to be used. If desired, the coils may be in several sections each section being fed by a pipe 8 and discharging into a pipe 9. In Figures 4, 5, and 7, only sections of the coil are shown with the other 40 sections broken away for the purpose of better illustrating my invention as in operation.

In Figure 1, the horizontal bus bar 11 is connected to a vertical bus-bar 12 which in turn is 45 electrically connected by suitable clamping members 14 to portions of the coil 5 and if desired, to the ground as indicated at 15. The bus bar 16 is similarly connected to a vertical bus bar 17 disposed adjacent the coil 5 and having thereon horizontally projecting contact portions 18 adapted to be connected by switch blades 19 see Fig. 2 of any suitable design to the horizontally contact projections 21 on the clamping members 22 which are connected at intermediate points on the coils 5. By this arrangement, it is possible to 50 55

place the switch blades 19 in such a position that they bridge the contact portions 18 and 21 either near the upper end or the lower end of the vertical bar 17 thereby selectively connecting the bus 17 with intermediate points on the coils 5.

The form of switch shown in Figure 2 comprises blades 19 extending parallel and supported by side bars 25. Plate members 26 are interposed between the bars 25 and the blades 19 for holding the ends of the bars 25 spaced from the sides of the blades 19 to accommodate the downwardly extending prongs 27 of the fork member 28 to which the handles 26 are secured. The fork members 28 are preferably of spring material to exert a pressure on the ends of the blades 19 and permit yielding of the blades laterally as they are pressed upon the cooperating contact portions 18 and 21.

The clamp 16 shown in Figure 3 is preferably formed of copper strapping or the like. It is preferably provided with openings 31 and 32 through which bolts may pass and by which the clamp may be securely held upon the refrigerating pipe and upon the bus bars.

In the operation of the system of the type disclosed, it is necessary to force a relatively large electric current through the coils 5 to heat them, the current being of relatively low voltage so as not to be dangerous. It is important, however, in applying the switch 19 and in removing the same, that the secondary 35 of the transformer 36 should be dead in order that the operator may not be burned by an electric arc. To determine whether or not the secondary is dead, I have provided a signaling system consisting of a buzzer 37 and a bell 38 permanently fixed directly across the secondary line so that whenever the secondary is excited, the signal will sound and be a warning to the operator not to touch the switch 19. In the secondary circuit I have also included a choke coil 39 to restrain surges which might otherwise be set up. The primary 41 of the transformer 36 is adapted to be connected directly above the line 42 by means of a switch 43, which is actuated by a coil 44 when the push button 45 is pressed down upon the contact points 46 and 47 to bridge the same and close the circuit therethrough. As the switch 43 is closed, a switch blade 49 is also closed upon the contact 51 which completes a holding circuit for the switch 43. In order to open the switch 43, it is necessary to press the push button 52 to break the connection between the contacts 53 and 54, thus interrupting the holding circuits for the switch 43.

In Figure 4 I have shown a common bus bar 12 connected at two points on the coil 5 and the secondary 35 of the transformer 36 connected between the bus bar 12 and an intermediate point 21 on the coil 5. In the modification shown in Figure 5, the coil 5 has interposed therein at certain points insulating couplings 56 which divide the coil 5 into a plurality of sections electrically insulated from all other sections. By this arrangement it is possible to connect the opposite sides of the secondary 35 of transformer to the coils 5 adjacent the insulator 56, without danger of causing stray currents to pass through other portions of the coil.

In Figure 6 the bus bar 12 connects several points 14 on the coil 5 but it is not directly connected to the transformer. In this case, the transformer is connected to intermediate points 58 and 59. If the bus bar 12 is grounded as at 15, in Figure 6, the opposite ends of the trans-

former secondary 35 impress potentials on the coil 5 at the points 58 and 59 which are higher and lower than ground potential but no stray currents pass through other coils that may be metallic connected therewith because the potentials impressed at 58 and 59 are reduced or increased as the case may be to ground potential at the points 14.

In Figure 7, I have shown a transformer having a primary 62 with a secondary divided into two sections 63 and 64 so connected with the coil 5 that the same potential is impressed on the coil 5 at the points 65 and 66 and a return conductor is connected between a central point on the transformer as at 67, and to an intermediate point 68 on the coil 5.

The diagrammatic illustration in Figure 8 represents an automatically operable control arrangement for closing the switches in the primary and secondary circuits of the transformer. The supply line is designated by numeral 42 and is connected to the conductors 71 and 72 which lead to the primary of the transformer 41 but is interrupted by the spaces between the switch contacts 73 and 74, which are adapted to be closed by the relay coil 75 upon closure of the contacts 76 and 77. The switch contacts 81 and 82 when closed complete the circuit through the secondary 35 of the transformer. These contacts 81 and 82 are adapted to be closed by the coil 83 when its circuit is completed through the contacts 84 and 85. The contacts 84 and 85 are closed by the coil 83 upon closure of the contacts 84 and 85. At 87 is designated a pushbutton and holding circuits therefor in the conductor 88 adapted when actuated to close the circuit through the control motor 89 which actuates a suitable form of contact drum or other control mechanism arranged to close the contacts 84' and 85' when actuated to excite coil 83 and close contacts 84' and 85' to excite the coil 83 and close the secondary circuit of the transformer and hold the same closed while the contacts 76 and 77 are closed to excite the coil 75 and effect the closing of the contacts 73 and 74 to close the primary circuit of the transformer. After the primary circuit has been closed a predetermined length of time it is again automatically opened before the opening of the secondary circuit.

By this arrangement it is possible to automatically close consecutive electric circuits through various sections of coil 5 and defrost the refrigerating coil section by section without interfering with the operation of the refrigerating plant and without interfering with the maintenance of a predetermined and constant temperature in the cooling compartment. It is possible to use many different forms of controlling apparatus to accomplish the connection of and disconnection of the circuits and I have illustrated diagrammatically in Figure 8 one such controlling apparatus by which the device may be operated.

I am aware that this device is susceptible of various changes and modifications without departing from the principles of this invention and I do not intend to limit the patent granted hereon except as required by the prior art.

I claim as my invention:

1. In a device of the class described, in combination, a refrigerating coil, a bus bar connected to said coil at a plurality of points, a second bus bar disposed adjacent said coil and adapted to be selectively connected to said coil

at a plurality of points intermediate the first mentioned points, automatic means for connecting said bus bar selectively to different points on said coil and subsequently connecting and disconnecting a source of potential between said bars.

2. In a device of the class described, in combination, a refrigerating coil, a bus bar connected to said coil at a plurality of points, a second bus bar disposed adjacent said coil and adapted to be selectively connected to said coil at a plurality of points intermediate the first mentioned points, automatic means for connecting said second bus bar selectively to different points on said coil and subsequently selectively connecting and disconnecting a source of potential with certain of said points of connection to complete an electric circuit through portions of said coil.

3. In a refrigeration system, a metallic refrigerant carrying pipe formed of a plurality of sections, said sections being adapted to form a part of an electric circuit, and insulating means connecting the sections adapted to offer a high resistance to current flow between the sections.

4. In a refrigerating system, a metallic refrigerant carrying coil, a bus structure positioned adjacent said coil, switch contacts on said bus structure, a source of current connected to said coil and to said bus structure, switch contacts carried supported by said coil and in conductive contact therewith, and switch means adapted to connect said bus switch with said coil supported switch contacts whereby sections of said coil may be selectively placed in circuit with said source.

5. In a refrigerating system, a metallic refrigerant carrying pipe, a source of current having terminals of opposite polarity, means to conductively connect a portion of said pipe to said terminals and in circuit with said source, and conductor means connecting portions of said pipe extending on either side of said first named portion to the electrical neutral of said circuit and to ground.

6. A refrigerating system for cold storage rooms and the like, said system comprising a metallic refrigerant carrying coil, and means to defrost portions of said coil while the system is normally active, said means comprising a plurality of relatively spaced switch contacts mounted supported on said coil to define between said contacts circuits of relatively short length, a bus structure having a plurality of switch contacts positioned adjacent said coil supported contacts, a source of energy having terminals of opposite polarity connected to said coil and to said bus structure, respectively, switch means to connect said bus contacts to said coil supported contacts to place

selected portions of said coil in circuit connection with said source, and conductor means connecting a plurality of points on said coil and to ground to maintain said connected points at ground potential.

7. In a refrigerating system, means including a metallic refrigerant carrying coil forming a closed conducting loop, a source of energy having terminals of opposite polarity, means to connect a section of said coil to said terminals to form an electric circuit, and conductor means connecting a point in said section intermediate its connection to said terminals in conductive connection with points on said coil extending on either side of said section, and other conductor means connecting said first named conductor means to ground.

8. In a refrigerating system, a metallic refrigerant carrying coil having a plurality of connected sections; conductor means connecting the ends of said sections to maintain said ends at a common electrical potential, a source of current having one of its terminals connected to said conductor means, and means adapted for connecting the other terminal of said source to selected points in said sections to include portions of said sections in circuit connection with said source.

9. The method of defrosting a refrigerating coil composed of a plurality of fluid connected sections which consists in conductively connecting the ends of the sections to maintain the ends at a common electrical potential, and connecting selected portions of the sections in circuit with a source of current having one of its terminals connected to the means conductively connecting the ends of the sections.

10. The method of defrosting a portion of a refrigerating system carrying metallic pipe while the refrigerating system is normally active, which method consists in including a portion of the pipe in circuit with a source of current and in connecting portions of the pipe extending on either side of the first named portion to the electrical neutral of the circuit and to ground.

11. The method of defrosting a portion of a refrigerating system carrying metallic coil while the refrigerating system is normally active, which method consists in placing a portion of the coil in circuit with a source of current and in conductively connecting portions of the coil outside of the portion included in the circuit to maintain said portions at a common electrical potential, and thereby prevent stray currents in these portions.

ISAIAH G. FURNAS. 56
